UNITED STATES PATENT OFFICE.

BENSON BIDWELL, OF CHICAGO, ILLINOIS.

CAR-MOTOR.

No. 845,682.

Specification of Letters Patent.

Patented Feb. 26, 1907.

Application filed July 5, 1906. Serial No. 324,777.

To all whom it may concern.

Be it known that I, BENSON BIDWELL, a citizen of the United States, residing at Chicago, in the county of Cook and State of Illinois, have invented certain new and useful Improvements in Car-Motors, of which the following, taken in connection with the accompanying drawings, is a description.

My invention has for its object the production of a motor adapted more particularly to be applied to trolley-cars and is so arranged that a cooling agent can be circulated within and through the armature and field-magnets, thereby keeping said armature and magnets cool and preventing a large proportion of the loss occasioned by said motors frequently burning out.

Heretofore in using a gearless motor it has been the custom to mount the fields on the trucks of the car with the armature on the axle, and in the event of any serious jarring of the car, caused by uneven tracks or the like, the fields and armature strike together and frequently destroy the armature-windings and other parts of the mechanism.

By my improved construction with the armature mounted upon the axle and the fields secured to a casing, hereinafter described, the entire mechanism moves in unison, thereby preventing any mechanical damage occasioned by the jarring of the moving car.

Another object of my invention is secured by mounting and arranging the armature and field-magnets so that I am enabled to use from four to six poles instead of two, as at present used on gearless motors. By this construction I am also enabled to run two armatures in parallel on the same axle, thereby doubling the amount of power and greatly reducing the cost of construction.

In the construction of my present invention I provide a cylindrical casing secured at the ends thereof to the inside of the wheels surrounding the axle and providing an air-chamber. This cylinder revolves with the car-wheels. Encircling said cylinder are stationary insulated rings through which contact is made with the brushes on the commutators and also, if desired, with the field-coils by the use of spring-adjusting trolley-wheels.

Other novel features and advantages of my invention will be hereinafter more fully pointed out in the following description.

The invention in this instance resides more particularly in the simplicity of the

combination and construction, arrangement, and adaptation of the different parts, which are illustrated in what I now consider the preferred form of my invention in the accompanying drawings, in which—

Figure 1 is a longitudinal cross-section taken through the center of the car axle and wheels. Fig. 2 is a transverse section taken on line 2 2 of Fig. 1. Fig. 3 is a like section taken on line 3 3 of Fig. 1. Fig. 4 is a diagrammatic view illustrating a modified form of connecting the field-magnets and the brushes.

In carrying out my invention, A represents a car-axle having mounted thereon the wheels B B, which may be of any ordinary type, and B' B' are the rails. A cylindrical casing C, secured at each end thereof to the wheels B, forms an air-tight chamber surrounding the aforesaid axle A between the wheels B B.

Armature-disks C' are mounted upon the axle A mediate of the length thereof, and each of the disks is said armature are provided with perforations for a purpose hereinafter described. Mounted upon the axle A are the insulating-collars D, which carry thereon the commutators D'.

D' are the line-wires.

d are the wires connecting the commutators and the armature.

d' are the wires connecting the brushes and the field-magnets, and d'' are the return-wires.

Secured to the casing C and coincident with the armatures C' are the field-magnets E and their windings e.

F are the brushes, which are held in contact with the commutators and are maintained in position by the compression-springs f f, surrounding the piston f' f''. Insulated sleeves G surround each one of the brushes F, extend through the casing C, and are provided with a metallic plate or cover G', which is secured to the casing C in any desired manner. The pistons f' f'' extend through the plates G' and have secured thereto the rings f' f'', which encircle the cylinder and revolve therewith.

Secured to the plate G of the casing is a circumferential slotted housing H, which moves with the cylinder C.

I represents the bottom of the car, and secured thereto are the hangers I', having a lining of insulating material i and provided with an inwardly-turned circumferential flange i', which forms an abutment for the

cap i^2 on the rod I^2 . Disposed between the housing H and the hangers I' are compression-springs i^3 . The lower end of each rod I^2 , which extends inside of the housing H , carries a harp J , in which is journaled a trolley-wheel J' , which wheel is held in frictional contact with the ring F' .

The axle A is provided with an inlet-opening a and an outlet-opening a' , extending inwardly from each end thereof to approximately the center of the armature C' for the purpose of permitting a cooling agent to be circulated therethrough and throughout the air-tight chamber formed by the casing C .

15 K is a tank or receptacle containing, preferably under pressure, a cooling agent to be used in connection with the apparatus herein described and which may be arranged in any convenient place upon the car. Connected therewith is a pipe or tube k . In operation the cooling-gas is preferably kept under pressure and is forced from the receptacle through the pipe k into and through the passage-way a , where it enters the armature, and through the openings c in the disks of the armature said cooling agent passes into the air-tight chamber and into contact with the field-magnets and other parts of the apparatus, thence through the second armature, 20 where it finds its exhaust through the passage-way a' to the outside atmosphere. If desired, said cooling agent might be returned to a condenser and used over again.

In the operation of the car it will be observed that the casing C , carrying with it the field-magnets E and brushes F , revolves with the wheels B B , while the axle, armature, and the commutators remain stationary.

I claim—

40 1. The combination of a stationary car-axle, wheels mounted thereon, a casing secured to said wheels and revolving therewith, an armature and commutator mounted upon the aforesaid axle, and field-magnets and

brushes secured to and revolving with the aforesaid casing.

2. The combination of a stationary car-axle and the wheels mounted thereon, said axle having inlet and outlet passage-ways, a cylindrical casing secured at each end thereof to said wheels and revolving therewith, an armature and commutator mounted upon said axle, field-magnets and brushes secured to said casing, and means for supplying a cooling agent to the interior of said casing and throughout the mechanism contained therein.

3. The combination of a stationary car-axle and the wheels mounted thereon, said axle provided with an inlet and an outlet passage-way through a portion of the length thereof, a cylindrical casing extending between the aforesaid wheels and secured thereto, armatures and commutators stationarily mounted upon said axle, field-magnets and brushes secured to the aforesaid casing and revolving therewith, and means for forcing a cooling agent through the aforesaid inlet passage-way and throughout the mechanism, substantially as described.

4. In a car-motor, the combination of a stationary axle and wheels rotatably mounted thereon, armatures and commutators mounted on said axle, a casing surrounding said armatures and commutators, brushes and field-magnets secured to and revolving with the aforesaid casing, contact-rings electrically connected with the commutator-brushes and the magnetic field, and trolley-wheels held in contact with the aforesaid rings, substantially as described.

In testimony whereof I have signed this specification in the presence of two subscribing witnesses.

BENSON BIDWELL.
